(57) **CLAIM**

The ornamental design for a smart watch, as shown and described.

DESCRIPTION

FIG. 1 is a front and right perspective view of a smart watch showing my new design;

FIG. 2 is a rear and left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view of FIG. 1;

FIG. 10 is a partially enlarged view of FIG. 3;

(Continued)

FIG. 11 is a partially enlarged view of FIG. 4; and, FIG. 12 is a partially enlarged view of FIG. 5. The broken lines encircling portions of the claimed design in FIGS. 1, and FIG. 3-6 that are illustrated in enlargements in FIGS. 9-12, respectively, form no part of the claimed design.
